UNITED STATES PATENT OFFICE.

JOHN J. VANECEK, OF CLEVELAND, OHIO.

FOUNTAIN PEN.

Application filed March 18, 1925. Serial No. 16,386.

To all whom it may concern:

Be it known that I, JOHN J. VANECEK, a citizen of the United States, residing at Cleveland, in the county of Cuyahoga and State of Ohio, have invented certain new and useful Improvements in Fountain Pens, of which the following is a specification.

This invention relates to improvements in fountain pens having for an object the provision of a structure which may be easily and quickly cleaned and wherein the quantity of ink contained in the reservoir may be ascertained when desired.

Another object is to provide a fountain pen in which the ink reservoir is removable with a suction bulb by means of which the reservoir may be filled from an ordinary ink bottle.

A further object is to eliminate entirely the necessity for inserting the pen carrying end of a fountain pen into an ink bottle in order to fill the reservoir.

It is likewise an object to generally simplify fountain pen construction and at the same time provide means for accommodating a materially greater quantity of ink than in the average pen.

Other objects will be in part obvious and in part pointed out hereinafter.

In order that the invention and its mode of operation may be readily understood by persons skilled in the art, I have in the accompanying illustrative drawings, and in the following detailed description based thereon set out the preferred embodiment of the same.

Figure 1 is a vertical longitudinal section of a fountain pen constructed in accordance with my invention, the cap being removed and shown in elevation;

Figure 2 is a side elevation of my improved fountain pen with the filling bulb cover detached;

Figure 3 is a side elevation of the filling bulb and ink reservoir;

Figure 4 is a detail view of the ink reservoir retaining member; and

Figure 5 is a sectional view taken substantially on the line 5—5 of Figure 2.

Similar characters of reference designate similar parts throughout.

This improved fountain pen may be constructed of any preferred material and comprises a barrel 6 having one end externally threaded as at 7 for engagement with inter-

ior threads of a cap member 8 which protects the pen 9.

This pen 9 is carried by a holder 10 whose inner end 11 is reduced in diameter and externally threaded to be engaged with interior threads at one end of the barrel 6. This reduced end 11 of the pen holder 10 abuts a soft rubber gasket or packing ring 12 which is provided with a tapered opening 13 whose function will be hereinafter apparent.

The opposite end of the fountain pen barrel 6 has a counterbore 14 which provides a shoulder 15 against which a metal ring or collar 16 of a reservoir retaining member bears. The outer end of this collar or ring 16 integrally carries a pair of curved yieldable spring fingers 17.

In providing an ink reservoir of unusual capacity and capable of ready removal from the barrel 6 I employ a structure closely resembling the usual eye dropper. The reservoir 18 consists of an elongated glass tube tapering at one end 19 for fitting in the tapered opening 13 of the previously mentioned gasket 12. This tapered end 19 has an opening 20 to permit injection and ejection of ink. The opposite end of the glass tube or reservoir 18, is reduced to form a neck 21 and is then flared outwardly as shown at 22 whereby the soft rubber filling bulb 23 may be securely engaged over said neck through the neck formation on the filling bulb. Figure 3 shows this structure and by reference to Figure 1 it is seen that this filling bulb and reservoir are arrangeable in fixed relation to the barrel 6 through snug engagement of the curved yieldable fingers 17 in the reduced neck portion. In the position shown in Figure 1 will be noted the gasket 12 cushions the glass tube and prevents passage of air or ink into the barrel 6. Obviously the proportionate sizes of the filling bulb and glass reservoir are such as to permit complete filling of the glass tube.

In a structure as herein described it is quite clear that it will be unnecessary to insert the pen into an ink bottle in order to fill the reservoir. Instead of the usual procedure I remove the filling bulb cover or cap 25 and then grasp the neck portion between the yieldable fingers 17 and withdraw the glass tube 18 from the barrel 6. I then take the removed portion completely illustrated in 110

Figure 3 and fill the glass tube 18 in the same manner that an ordinary eye dropper is filled, after which the reservoir is replaced as indicated in Figure 1. A pen constructed as stated eliminates the necessity of guess work as to the quantity of ink contained in the ink reservoir; provides a reservoir of greater capacity than in the average pen; and eliminates the very objectionable soiling of the fingers which results where the pen itself must be inserted into an ink bottle for filling.

Manifestly, the construction shown is capable of certain modification and such modification as may fall within the scope of the appended claims, I consider within the spirit of my invention.

I claim:

1. A fountain pen comprising a barrel, a pen, an ink reservoir removably arranged in the barrel, a filling bulb fixed to the reservoir and removable therewith, and means for holding the bulb and reservoir in fixed relation to the barrel.

2. A fountain pen comprising a barrel, a pen, an ink reservoir removably arranged in the barrel, a filling bulb fixed to the reservoir and removable therewith, spring means arranged to releasably hold the bulb and reservoir in fixed relation to the barrel.

3. A fountain pen comprising, a barrel, a pen, an ink reservoir removably arranged in the barrel, a filling bulb fixed to one end of the reservoir, and spring fingers carried by the barrel to releasably retain the bulb and reservoir in the barrel.

4. A fountain pen comprising, a barrel, a

pen, an ink reservoir removably arranged in the barrel, a filling bulb, said reservoir having a reduced neck at one end to fit into the bulb, and yieldable fingers arranged to fit into the neck portion and releasably retain the reservoir and bulb in the barrel.

5. A fountain pen comprising, a barrel, a ring-like gasket near one end, a reservoir having a tapered open end seatable in the gasket, a reduced neck portion at the other end of the reservoir, a filling bulb having one end fitted over said neck portion, and means engaging the neck portion to releasably retain the reservoir and bulb in fixed relation to the barrel.

6. A fountain pen comprising, a barrel, a ring-like gasket near one end, a reservoir having a tapered open end seatable in the gasket, a reduced neck portion at the other end of the reservoir, a filling bulb having one end fitted over said neck portion, and spring means engaging the neck portion to releasably retain the reservoir and bulb in fixed relation to the barrel.

7. A fountain pen comprising, a barrel, a ring-like gasket near one end, a reservoir having a tapered open end seatable in the gasket, a reduced neck portion at the other end of the reservoir, a filling bulb having one end fitted over said neck portion, a collar carried by the barrel, and spring fingers engageable in said neck portion to releasably retain the reservoir and bulb in fixed relation to the barrel.

In testimony whereof, I affix my signature.

JOHN J. VANECEK.
